SUPERVISORY SYSTEM

Clyde E. Stewart, Upper Darby, Pa., assignor to
 General Electric Company, a corporation of
 New York

Application November 7, 1939, Serial No. 303,237

6 Claims. (Cl. 177—353)

My invention relates to supervisory systems and particularly to supervisory systems of the cable type in which control and indicating impulses are directly transmitted between each apparatus unit and the control station over conductors individual to each unit. Heretofore, in supervisory systems of the cable type, it has been the practice to provide, in addition to the common battery conductors extending between the apparatus units and the control station, a pair of conductors for each apparatus unit, one of each pair being a control conductor and the other an indication conductor.

One object of my invention is to provide an improved cable type supervisory system which requires a smaller number of conductors between the control station and the various apparatus units than has been required in previous systems of this type.

Another object of my invention is to provide a cable type supervisory system which employs only three common conductors and an individual conductor for each apparatus unit in addition to the common battery conductors between the control station and the various apparatus units.

My invention will be better understood from the following description when taken in connection with the accompanying drawing the single figure of which diagrammatically illustrates a cable type supervisory system embodying my invention, and its scope will be pointed out in the appended claims.

In the accompanying drawing AU1 and AU2 represent two of a plurality of remote apparatus units which are arranged to be controlled and supervised from a control station CS. As shown, the apparatus units AU1 and AU2 are circuit breakers of the well known latched-in type and are respectively provided with suitable closing coils CC1 and CC2 and trip coils TC1 and TC2. The circuit of each trip coil is arranged to be completed by an associated overcurrent relay, such as relays OC1 and OC2 for trip coils TC1 and TC2 respectively, which is so connected as to be responsive to an abnormal current through the associated circuit breaker. The circuit of each trip coil is also arranged to be completed by an associated control relay, such as relays CR1 and CR2 for trip coils TC1 and TC2 respectively, when it is energized. The circuit of each closing coil is arranged to be completed by an associated control relay, such as relay CCR1 and CCR2 for closing coils CC1 and CC2 respectively, when it is energized. Each apparatus unit also has associated therewith an individual selection relay,

such as relays SR1 and SR2 for the apparatus units AU1 and AU2 respectively, which, when energized, connects the associated closing control relay and tripping control relay, respectively, to the common close and trip conductors CC and TC which extend from control station CS to all of the apparatus units.

At the control station an individual group of control keys and signal lamps is provided for each remote apparatus unit to be supervised and controlled therefrom. The individual group of control keys for apparatus unit AU1 comprises a two-position select key SK1, which is moved from its normal position, which is the position in which it is shown, to its selecting position when it is desired to control apparatus unit AU1 from control station CS, and a two-position disagreement key DK1, which controls by its position the lighting of an associated white lamp LW1 so that it is lighted when the position of key DK1 does not agree with the position of the associated apparatus unit AU1. The individual group of signal lamps for apparatus unit AU1 also includes a red lamp LR1, which, when lighted, indicates that apparatus unit AU1 is in its closed position, a green lamp LG1, which, when lighted, indicates that apparatus unit AU1 is open and an amber lamp LA1, which, when lighted, indicates that the associated apparatus unit AU1 has been selected so that the operation of a master control key MCK, which is common to all of the apparatus units and which is located at the control station CS, can effect the closing of apparatus unit AU1, if it is open, and the operation of a similar master trip key MTK at the control station CS can effect the opening of apparatus unit AU1, if it is closed.

The individual group of control keys and signal lamps for the apparatus unit AU2 consists of a similar select key SK2, disagreement key DK2, white lamp LW2, red lamp LR2, green lamp LG2 and amber lamp LA2.

The red and green lamps for each group of signaling lamps are connected respectively between the positive and negative terminals of a suitable battery B and one end of an individual indication and selection conductor, the other end of which is connected in series with the energizing winding of an associated selection relay to either the positive or the negative terminal of the battery B, depending upon the position of the associated apparatus unit. For example, one end of the indication and selection conductor IS1, which is individual to apparatus unit AU1 and extends from control station CS to appara-

tus unit AU₁, is connected to the positive terminal of battery B through red lamp LR₁ and to the negative terminal of the battery B through green lamp LG₁. The other end of conductor IS₁ is arranged to be connected in series with the operating winding OW of selection relay SR₁ to the positive terminal of battery B through the contacts d of apparatus unit AU₁, if it is open, or to the negative terminal of battery B through the contacts c of apparatus unit AU₁, if it is closed. Similarly, one end of the indication and selection conductor IS₂, which is individual to apparatus unit AU₂ and extends from control station CS to apparatus unit AU₂, is connected to the positive terminal of battery B through red lamp LR₂ and to the negative terminal of battery B through green lamp LG₂. The other end of conductor IS₂ is connected in series with the operating winding OW of selection relay SR₂ to the positive terminal of battery B through the contacts d of apparatus unit AU₂, if it is open, and to the negative terminal of battery B through the contacts c of apparatus unit AU₂, if it is closed.

Therefore, it will be seen that the red and green lamps of each group of signal lamps are selectively lighted in accordance with the position of the corresponding apparatus unit. The operating windings of the selection relays are marginal so that the current that normally flows through each individual indication and selection conductor and the winding OW of the associated selection relay to light the associated signal lamps, however, is not sufficient to effect the operation of the relay.

While I have shown a single battery B, it will be obvious that a separate battery at the control station and at the remote station, where the apparatus units are located, may be used instead and in that case only the neutral terminals of the two batteries need to be interconnected directly by conductors extending between the two stations.

Each white lamp is connected in series with the normally closed contacts b of the associated select key between the associated indication and selection conductor and either the positive or negative terminal of battery B depending upon the position of the associated disagreement key. For example, when disagreement key DK₁ is in the position in which it is shown, which is the position thereof corresponding to the closed position of the associated apparatus unit AU₁, a circuit is completed from conductor IS₁ through white lamp LW₁, contacts b of select key SK₁, contacts b of disagreement key DK₁, winding of relay AT to the negative terminal of battery B. When disagreement key DK₁ is in its other position, which is the position thereof corresponding to the open position of apparatus unit AU₁, a circuit is completed from conductor IS₁ through white lamp LW₁, contacts b of select key SK₁, contacts a of disagreement key DK₁, winding of relay AC to the positive terminal of battery B. When either relay AC or AT is energized, the operation of an associated pilot lamp relay PLR is effected to complete a circuit for a pilot lamp PL which remains lighted until the operator manually opens a pilot light key PLK. The lighting of the pilot lamp PL informs the operator that one of the apparatus units has automatically operated.

Each select key, when moved to its selecting position, completes an energizing circuit for the

operating winding OW of the associated switching relay. For example, when select key SK₁ is moved to its selecting position, an energizing circuit is completed for operating winding OW of switching relay A₁ through contacts a of select key SK₁, contacts b of a control relay AX if all of the other select keys are in their normal positions and contacts b of relay CW if line wires CC and TC are free from positive potential. By closing its contacts a, switching relay A₁ completes an energizing circuit for its holding winding HW through contacts c of the associated select key SK₁ and the winding of the common control relay AX, which by opening its contacts b, insures that no other switching relay can be energized while relay A₁ is energized.

By closing its contacts c, each switching relay prepares a circuit between its associated indication and selection conductor and the neutral terminal of battery B, which is completed through the contacts a of a common start key STK when it is moved to its starting position. The operation of start key STK, while the common control relay AX is energized, also completes through contacts c of start key STK an energizing circuit for an associated start relay STR, which in turn completes a locking circuit for itself, which is independent of the position of start key STK.

The increase in current in an indication and selection conductor, which occurs when it is connected directly to the neutral terminal of battery B in response to the operation of start key STK, causes the marginal operating winding OW of the associated selection relay to be energized sufficiently to effect the operation of the relay so that the closing control relay and tripping control relay of the associated apparatus unit are respectively connected to the common closing conductor CC and the common tripping conductor TC respectively. Also, by closing its contacts a, the selection relay connects its holding winding HW between the neutral terminal of battery B and a common indicating conductor IC which extends from the control station to all of the apparatus units.

At control station CS, start relay STR, when energized, completes through the common indicating conductor IC an energizing circuit for the amber lamp associated with the operated select key when the corresponding selection relay is in its operated position. The lighting of an amber lamp informs the operator that the corresponding apparatus unit has been selected and may be opened or closed by operating master close key MCK or master trip key MTK.

A start lamp STL is provided at control station CS and is controlled by start relay STR and the common control relay AX so that it is lighted when the supervisory system is in an operative condition to make a selection.

When the system is at rest, the common close conductor CC and the common trip conductor TC are respectively supervised against possible external applications of potential which might otherwise cause an operation of an apparatus unit after it has been selected. At control station CS, the common close conductor CC is normally connected to the negative terminal of battery B through winding X of a two-winding relay CW, when master close key MCK is in its normal position, and the common trip conductor TC is normally connected to the negative terminal of battery B through the other winding y of relay CW when master trip key MTK is

in its normal position. Therefore, if a potential exists between either conductor CC or conductor TC and the negative terminal of battery B, relay CW operates and interrupts the energizing circuits of the operating windings OW of all of the switching relays and also causes start lamp STL to be extinguished and pilot relay PLR to be energized to effect the lighting of pilot lamp PL.

The operation of the system shown in the drawing is as follows:

With the system at rest and in an operative condition and all of the apparatus units in their closed position, the various control devices are in the positions in which they are shown in the drawing. Start lamp STL is lighted by a circuit which is completed from the positive terminal of battery B through contacts b of relay CW, contacts b of relay AX, and contacts b of start relay STR. Red lamp LR1 is lighted by a circuit which is completed from the negative terminal of battery B through contacts c of apparatus unit AU1, winding OW of selection relay SR1, conductor IS1, lamp LR1 to the positive terminal of battery B. The current in this circuit, however, is not sufficient to effect the operation of selection relay SR1. Lamp LR2 is lighted by a similar circuit which is completed through contacts c of apparatus unit AU2, winding OW of selection relay SR2 and conductor IS2.

It will now be assumed that the operator at control station CS desires to open apparatus unit AU2. After first noting that start lamp STL is lighted, the operator moves select key SK2 to its selecting position and disagreement key DK2 to its other position, which corresponds to the open position of apparatus unit AU2, and then momentarily moves start key STK to its starting position. The closing of contacts a of select key SK2 completes an energizing circuit for operating winding OW of switching relay A2 from the positive terminal of battery B through contacts b of relay CW, contacts b of relay AX, contacts a of select key SK2, winding OW of relay A2 to the negative terminal of battery B. The closing of contacts a of relay A2 completes an energizing circuit for its holding winding HW and for relay AX from the positive terminal of battery B through the contacts c of select key SK2, contacts a of relay A2, winding HW of relay A2, winding of relay AX to the negative terminal of battery B. The opening of the contacts b of relay AX prevents the operating winding circuit of any other switching relay from being completed as long as switching relay A2 remains energized. The opening of contacts b of relay AX also interrupts the circuit of start lamp STL so that it becomes extinguished.

The movement of disagreement key DK2 to its other position does not effect the lighting of white lamp LW2 at this time because the circuit of this lamp is open at contacts b of the operated select key SK2.

When start key STK is moved to its starting position, a circuit is completed for start relay STR from the positive terminal of battery b through contacts c of start key STK, contacts a of control relay AX, winding of relay STR to the negative terminal of battery B. By closing its contacts a, start relay STR completes a locking circuit for itself around contacts c of start key STK. The closing of contacts a of start key STK connects indication and selection conductor IS2 directly to the neutral conductor of battery B through contacts c of the energized switching relay A2 so that the current through operating

winding OW of selection relay SR2 increases to such a value that relay SR2 operates. By closing its contacts c and e, relay SR2 respectively connects closing control relay CCR2 and tripping control relay CR2 to conductors CC and TC. Relay SR2 also completes an energizing circuit for its holding winding HW from the neutral terminal of battery B through winding HW of relay SR2, contacts a of relay SR2, common indication conductor IC, contacts c of start relay STR, contacts e of switching relay A2, amber lamp LA2, contacts c of disagreement key DK2 to the positive terminal of battery B. The current in this circuit lights amber lamp LA2 which informs the operator that apparatus unit AU2 has been selected.

After amber lamp LA2 becomes lighted, the operator moves master trip key MTK to its tripping position so that an energizing circuit is completed for control relay CR2 from the positive terminal of battery B through contacts e of start relay STR, contacts a of faster trip key MTK, conductor TC, contacts e of selection relay SR2, winding of control relay CR2 to the negative terminal of battery B. The closing of contacts a of control relay CR2 completes through auxiliary contacts a of apparatus unit AU2 an energizing circuit for trip coil TC2 to effect the opening of apparatus unit AU2. By opening its auxiliary contacts d, apparatus unit AU2 transfers the remote end of conductor IS2 from the negative terminal to the positive terminal of battery B. Consequently red lamp LR2 is extinguished and green lamp LG2 is lighted to inform the operator that apparatus unit AU2 is in its open position.

If the operator desires to reclose apparatus unit AU2, he closes master close key MCK so that an energizing circuit is completed for closing control relay CCR2 from the positive terminal of battery B through contacts e of start relay STR, contacts a of master close key MCK, conductors CC, contacts c of selection relay SR2, contacts b of apparatus unit AU2, closing control relay CCR2 to the negative side of battery B. The closing of contacts a of closing control relay CCR2 completes an energizing circuit for closing coil CCI to close apparatus unit AU1. By opening its auxiliary contacts b and closing its auxiliary contacts a, apparatus unit AU2 causes green lamp LG2 to be extinguished and red lamp LR2 to be lighted to indicate to the operator that apparatus unit AU2 is in its closed position.

After the operator has operated apparatus unit AU2 to the desired position, he restores select key SK2 to its normal position thereby effecting the deenergization of switching relay A2, control relay AX and starting relay STR at control station CS and the deenergization of selection relay SR2 at the remote station where apparatus unit AU2 is located. The apparatus is thereby restored to its normal position and start lamp STL is again lighted.

It will now be assumed that apparatus unit AU1 is automatically opened in response to overcurrent relay OC1 closing its contacts a and completing through auxiliary contacts a of apparatus unit AU1, an energizing circuit for trip coil TC1. By opening its auxiliary contacts c and closing its auxiliary contacts d, apparatus unit AU1 transfers the remote end of conductor IS1 from the negative terminal to the positive terminal of battery B so that red lamp LR1 is extinguished and green lamp LG1 is lighted. Also

a circuit is completed through white lamp LW1 and winding of relay AT from the positive terminal of battery B through auxiliary contacts *d* of apparatus unit AU1, operating winding OW of selection relay SRI, conductor IS1, white lamp LW1, contacts *b* of select key SK1, which is now in its normal position, contacts *b* of disagreement key DK1, winding of relay AT to the negative terminal of battery B. The current in this circuit is not sufficient to operate selection relay SRI but is sufficient to operate relay AT. By closing its contacts *a*, the relay AT completes an energizing circuit for the winding of pilot lamp relay PLR across the positive and negative terminals of battery B. By closing its contacts *a*, relay PLR completes a locking circuit for itself through the normally closed contacts of pilot lamp key PLK and by closing its contacts *c*, relay PLR completes across the positive and negative terminals of battery B a circuit for lighting pilot lamp PL. By closing its contacts *e* relay PLR completes a short-circuit around the winding of relay AT. This feature maintains full voltage on the white lamps in case several are operated simultaneously. After the operator has been informed by the lighting of pilot lamp PL and white lamp LW1 that apparatus unit AU1 has been automatically tripped, he can select and reclose it in the usual manner or leave it in the open position. He extinguishes the white lamp LW1 by moving disagreement key DK1 to the position thereof corresponding to the open position of apparatus unit AU1. He then extinguishes pilot lamp PL by momentarily opening key PLK in the locking circuit of relay PLR.

While I have, in accordance with the Patent Statutes, shown and described my invention as applied to a particular system and as embodying various devices diagrammatically indicated, changes and modifications will be obvious to those skilled in the art, and I therefore aim in the appended claims to cover all such changes and modifications as fall within the true spirit and scope of my invention.

What I claim as new and desire to secure by Letters Patent of the United States is:

1. In a supervisory system, a control station, a plurality of remote apparatus units, an individual conductor from each unit to said station, a battery, means associated with each apparatus unit for selectively connecting the adjacent end of the associated individual conductor to different terminals of said battery in accordance with the position of the unit, individual signaling means at said station for each apparatus unit selectively controlled in accordance with the terminal of said battery to which the remote end of the associated individual conductor is connected, an individual control winding associated with each apparatus unit, a control conductor extending from said station to all of said apparatus units, individual selective relays associated with each control winding for connecting it to said control conductor, each relay having an operating winding connected in series with the respective individual conductor and a holding winding, a second conductor extending from said station to all of said apparatus units, means at said control station for controlling the current in an individual conductor so as to effect the operation of the associated selective relay, means responsive to the operation of a selective relay for completing an energizing circuit for the associated holding winding through said second conductor in-

dependently of the position of the associated unit, means responsive to the energization of said second conductor for operating the individual signaling means corresponding to the operated selective relay to indicate that said relay has been operated and means at said control station for controlling the energization of any control winding connected thereto.

2. In a supervisory system, a control station, 10 a plurality of remote apparatus units, an individual conductor from each unit to said station, a battery, means associated with each apparatus unit for selectively connecting the adjacent end of the associated individual conductor to different terminals of said battery in accordance with the position of the unit, individual signaling means at said station for each apparatus unit selectively controlled in accordance with the terminal of said battery to which the remote end 15 of the associated individual conductor is connected, an individual control winding associated with each apparatus unit, a control conductor extending from said station to all of said apparatus units, individual selective relays associated with each control winding for connecting it to said control conductor, each relay having an operating winding connected in series with the respective individual conductor and a holding winding, a second conductor extending from said station to all of said apparatus units, individual switching means at said control station for each unit for controlling the current in the associated individual conductor so as to effect the operation of the associated selective relay, a signal at said control station individual to each unit, means responsive to the operation of a selective relay while the associated individual switching means is operative for completing through said second conductor a series circuit 20 for the associated holding winding and signal, and means at said control station for controlling the energization of any control winding connected thereto.

3. In a supervisory system, a control station, 25 a plurality of remote apparatus units, an individual conductor between said station and each unit, a battery, means associated with each apparatus unit for selectively connecting the associated conductor to the positive and negative terminals of said battery in accordance with the position of the apparatus unit, a lamp at said control station individual to each unit, a two-position disagreement key at said control station individual to each unit for selectively connecting the associated lamp between the associated individual conductor and the positive and negative terminals of said battery, a signal, and means responsive to a predetermined current through any lamp for effecting the operation of 30 said signal and an increase in the current through the lamp.

4. In a supervisory system, a control station, 35 a plurality of remote two-position apparatus units, an individual signal conductor between said station and each unit, a battery, means associated with each apparatus unit for selectively connecting the associated conductor to the positive and negative terminals of said battery in accordance with the position of the apparatus unit, a lamp at said control station individual to each unit, a disagreement key at said control station individual to each unit and having positions corresponding to the positions of the 40 associated unit in which it connects the asso-

ciated lamp between the associated individual conductor and the terminal of said battery so that both ends of a conductor are connected to the same terminals of said battery when an apparatus unit and the associated disagreement key are simultaneously in corresponding positions, a signal, and means responsive to a predetermined current through any lamp for effecting the operation of said signal and an increase in the current through the lamp.

5. In a supervisory system, a control station, a plurality of remote apparatus units, an individual conductor between said control station and each apparatus unit, a control conductor common to said station and all of said apparatus units, an individual winding associated with each apparatus unit and normally disconnected from said control conductor, individual selective means for connecting each apparatus unit winding to said common conductor, individual control means at said control station for operating each selective means over the associated individual conductor, means at said control station for controlling the energization of an apparatus unit winding connected to said 25 control conductor, a second conductor common to said station and all of said apparatus units, individual signaling means at said station for each control means, and means responsive to the simultaneous operation of an individual con-

30 trol means and an individual selective means for completing over said second conductor an operating circuit for the signaling means associated with the operated control means.

6. In a supervisory system, a control station, a plurality of remote apparatus units, an individual conductor between said control station and each apparatus unit, a control conductor common to said station and all of said apparatus units, an individual winding associated with each apparatus unit and normally disconnected from said control conductor, individual selective means for connecting each apparatus unit winding to said common conductor, individual control means at said control station for operating each selective means over the associated individual conductor, means at said control station for controlling the energization of an apparatus unit winding connected to said 20 control conductor, a second conductor common to said station and all of said apparatus units, an individual signal lamp at said station associated with each control means, and means responsive to the simultaneous operation of an individual control means and an individual selective means for completing through said second conductor an operating circuit for the signal lamp associated with the operated control means.

CLYDE E. STEWART.
